SWIMMING MASK

Bernard Schwartz, Philadelphia, Pa., assignor to Globe Rubber Products Corporation, Philadelphia, Pa., a corporation of Pennsylvania

Filed Aug. 1, 1960, Ser. No. 61,582

Term of patent 14 years

(Cl. D83—1)

FIG. 1 is a front view of a swimming mask embodying my new design;

FIG. 2 is a top view thereof;

FIG. 3 is a side view thereof;

FIG. 4 is a sectional view thereof taken in the direction of the lines and arrows 4—4 in FIG. 1; and

FIG. 5 is a sectional view thereof taken in the direction of the lines and arrows 5—5 in FIG. 1.

I claim:

The ornamental design for a swimming mask, as shown.
